UNITED STATES PATENT OFFICE.

ISAAC BELLOCH, OF NEW YORK, N. Y.

NONSET AUTOMATIC STOP MECHANISM.

Application filed June 21, 1921. Serial No. 479,174.

To all whom it may concern:

Be it known that I, ISAAC BELLOCH, a citizen of the United States, residing at New York city, in the county of New York, State 5 of New York, have invented certain new and useful Improvements in Nonset Automatic Stop Mechanism, of which the following is a description, reference being had to the accompanying drawing and to the figures of reference marked thereon.

This invention relates to non-set automatic stop mechanism for phonographs.

The main object of this invention is to provide a simple, inexpensive mechanism 15 which is operative upon cessation of playing of a record to automatically trip the brake mechanism of the phonograph, irrespective of the length of the record and without any adjustment of the brake tripping mechanism for the length of the particular record to be played.

A further object of this invention is to provide means to prevent operation of the brake tripping mechanism while setting the 25 tone arm in its initial groove.

A still further object is to provide means for preventing premature tripping of the brake mechanism during playing of the record.

30 Another object of the invention is to provide means for preventing the tripping of the brake mechanism while moving the tone arm laterally to record playing position.

Still another object of the invention is to 35 provide means whereby the automatic tripping mechanism may be rendered inoperative so as to permit wholly manual control of the brake tripping mechanism.

Other and further objects will appear after reading the following specification and 40 claims in connection with the accompanying drawings, in which

Figure 1 is a plan view of my tripping mechanism as applied to a phonograph, the 45 outline of the turntable being shown in dotted lines.

Figure 2 is an elevation of a fragmentary portion thereof.

Figure 3 illustrates one of the positions 50 assumed by a tripping pin and arm forming a portion of my tripping mechanism.

Figure 4 illustrates another position assumed by the same parts with the trip pin effective to release the brake lever.

55 Figure 5 is a modified form of tripping pin.

Figure 6 illustrates the position assumed by a trip arm restoring spring during initial playing of the record.

Figure 7 illustrates another position of 60 the same parts assumed during the playing of the final portion of the record.

Figure 8 is a section through a portion of my trip arm driving mechanism.

Figure 9 is an elevation of the same, a 65 spring detent being shown in dotted lines, and

Figure 10 is a plan view of the same.

Now referring to the several figures more 70 in detail, 1 indicates the table of a phonograph cabinet through which projects the spindle 2 for driving the turntable 3.

Also rotatably mounted on the table is the tone arm 4 shown only fragmentarily in Figure 2 and the post of which is shown in section 75

in Figure 1. Secured to the post of the tone arm 4 as by means of screws 5 is a seg- 80

mental rack 6, the same being spaced from the tone arm by means of a support having reaches 7.

Cooperating with the rack is a 85 pinion 8, the same being rigidly secured to a shaft 9 stepped in a base plate 10.

Supporting the upper end of the shaft is the Z-shaped bracket 11, secured at its lower end to the base plate by means of screws 12, al- 90

though it is of course understood that the same may be brazed, welded or otherwise secured thereto.

The base plate 10 has an extension 59 provided with upstanding ears 60 and 61 and a horizontal projection 14.

Secured to the ear 60 is a spring detent 15, said detent cooperating with a fine toothed pinion 16 freely rotatable on the shaft 9.

This detent permits clockwise rotation of the pinion 16 as viewed in Fig. 1 but pre- 95

vents anti-clockwise rotation thereof. Rest- 100

ing on the upper face of the pinion 16 and rotatable about a group of pins 18 circum- 105

ferentially arranged on and secured to or integral with the pinion 16 is the hub of a trip arm 19, and resting on the hub is the 110

pawl carrier 20, the same constraining the pinion 16 to move therewith by reason of the pins 18 projecting within apertures 21

in the carrier 20. Also secured to the shaft 9 as by a pin 17 is the ratchet 22, the teeth 115

of which engage a spring pressed pawl 23 mounted on the carrier 20 to drag the pawl and carrier around in clockwise rotation.

It is to be understood that the arm 19 is 120 clamped between the pinion 16 and the pawl carrier 20 sufficiently to drag the same with

them upon rotational movement thereof but yet the frictional contact is loose enough to permit movement of the arm 19 relative to the shaft 9 upon application of a slight external force tending to rotate the arm about the shaft as an axis. It will now be understood that as the tone arm moves to the left in Fig. 1, the rack 6 moves therewith, which so rotates the pinion 8 and through it the 10 ratchet 22, ratchet carrier 20 controlled thereby and pins 18, as to cause the arm 19 to move in the same direction as the tone arm. To move the arm 19 in the opposite direction, a pin 24 is provided, the same being mounted on a pulley 25 journaled on a bearing 30 secured on a brake plate 21, said pulley being driven from the spindle 2 by means of a belt 26 trained over the pulley 25 and a second and smaller pulley 27 fastened 15 to the spindle 2. The arm 19 at its free end is bifurcated to provide prongs 28 and 29, the pin engaging the prong 28 to move the arm 19 to one position and the prong 29 to another and brake tripping position as will 20 be explained shortly.

To brake the turntable a bell crank brake lever 32 is provided, the same being mounted on a stud 33 secured in the brake base plate 31, one end of the lever being provided with 25 a rubber or felt washer 34 to engage the flange of the turntable and the other end being provided with a resetting handle 35 to release the brake. To urge the brake lever toward braking position, a spring 36 is provided as may be readily understood. To restrain the brake in non-braking position, a notched brake tripping lever 37 is provided, in the notch of which a pin 38 secured to the brake lever is retained. The lever 37 30 has an elongated arm 39 provided at its free end with an upstanding portion 40 in the path of movement of arm 19. It will now be understood that upon sufficient movement of the arm 19, the arm 39 will be moved 35 to release the brake mechanism to thereby stop the turntable from rotating. A manual trip is provided in the form of a stud 41 formed on or secured to the lever 37. To limit the movement of the arm 19 in its 40 clockwise movement an abutment arm 42 is adjustably mounted on base plate 10 as by a slot and screw adjustment 43, said arm at its free end being suitably provided with a sound deadening bumper 44 of felt or 45 rubber.

Pivottally mounted on the ear 13 is a lever 45, one end of which is provided with a lip 46 which at times is adapted to engage beneath the rack 6 in order to maintain the 50 opposite and heavier end 47 of the lever in elevated position. It can be readily seen, however, that when the rack is moved clockwise a few degrees, that the lip 46 is released to thereby permit the opposite end of 55 lever 45 to be depressed. The end 47 serves

during the playing of the initial portion of the record to cause a spring member 48 pivoted on a pintle 49 secured to the extension 14 of the base plate 10 to be raised in position to resiliently engage the arm 19 70 when it is swung to the position indicated in Fig. 3 to thereby restore it to the position shown in Fig. 1.

The operation of the device will now be described. Normally the parts are arranged 75 as shown in Fig. 1. When the spindle 2 begins to rotate, the pulleys 27 and 25, and consequently the pin 24, all rotate in a clockwise direction. The pin 24 engages the prong 28 and moves the arm 19 over one step 80 as shown in Fig. 3. At this time, however, the arm 19 is resiliently engaged by the spring 48 and when the pin 24 passes out of the bifurcation of the arm 19 the same is pushed back toward the position shown 85 in Fig. 1. This operation is repeated until the tone arm has traveled along the record sufficiently to cause the rack 6 to release the lip 46 of the lever 45. The end 47 now is depressed so that the spring 48 is no longer 90 in the path of travel of the arm 19. Under these conditions, when the pin 24 has moved the arm 19 to the position shown in Fig. 3, there is no spring force tending to restore the arm 19 to its original position. At this 95 time, however, the movement of the rack 6 rotates the pinion 8 to thereby frictionally drag the arm 19 as explained heretofore to the position shown in Fig. 1. This operation is repeated until the tone arm and consequently the rack stops moving, whereupon the arm 19 is left in the position indicated in Fig. 4 until the pulley 25 makes a complete revolution and the pin engages the prong 29 to further move the arm 19 so as 100 to cause the same to engage projection 40 on arm 39 to trip the brake. It can be readily seen that in the absence of the spring 48 and controlling mechanism therefor, the pin 24 may successively engage prongs 28 105 and 29 to thereby cause an undesired and inadvertent tripping of the brake mechanism while the tone arm is being held in the hand to set the same in the first groove or while the turntable is speeding up to record playing speed. 110

With mechanisms of the prior art, the brake mechanisms frequently are tripped during playing of the record due to swaying of the tone arm back and forth when playing a warped or otherwise imperfect record; with my invention, due to the provision of the knurled surface, which may be as fine as may be desired, on the pinion 16, and the spring detent 15, the swaying of the tone 125 arm in one direction is not imparted to the arm 19, thereby preventing accidental contact of the arm 19 with the projection 40; the backward movements of the tone arm merely cause the ratchet to move anti-clock- 130

wise, Fig. 10, relative to the ratchet carrier 20 and the remaining mechanism. In like manner when the tone arm is moved to replay a record or some intermediate portion 5 thereof, the brake mechanisms will not be automatically tripped. On the other hand the ratchet mechanism 22, 23 operates to cause clockwise movement of the arm 19 upon clockwise movement of any character 10 of the tone arm.

The angular distance moved over by the arm 19 relative to the angular movement of the tone arm may be chosen as desired by properly positioning the rack from the center 15 of curvature and by properly choosing the character of the pinion and the fineness of teeth. Likewise the period of time within which the arm 19 may be restored to the position illustrated in Fig. 1 may be predetermined by the ratio of the diameter of pulleys 27 and 25.

To provide against the contingency of the failure of the device to operate due to the pin striking against the point of a 25 prong 28 or 29, a two part pin, as illustrated in Fig. 5, may be employed, the same comprising a butt end 50, which may be inserted in the pulley 25, and two members 51 and 52 pivoted on a pintle 53 and 30 resiliently maintained in the position shown by a leaf spring 54. If now the pin should strike head on against the point of a prong, the top portion would be bent back to permit the pin to pass underneath the arm 19 35 and upon the next revolution of the same, a side of the pin would probably engage a side of one of the prongs to move the arm 19. The pin, of course, is positioned so that it can be bent back only when striking 40 head on against a point of the prongs.

The arm 19 is made extensible by the provision of a pin and slot connection 55 to accommodate the device to different distances between tone arm and spindle 45 centers.

In order to be able to render the entire automatic device inoperative, the frame 10 is secured to the table at one end by a single screw 56, while a screw 57 passes 50 through an arcuate slot 58 in the member 11. By loosening the screws 56 and 57, it is evident that the frame 10 together with the shaft and all it carries may be swung out of operative engagement with the rack 55 6 and the pin 24.

Having thus described my invention, what I claim as new is:

1. In a phonograph, a tone arm, a braking mechanism including an oscillatable arm, means for oscillating said arm, and additional means for moving said arm comprising a lever, arm actuating means controlled by said lever and cam mechanism controlled by said tone arm for pivoting 60 said lever.

2. In a phonograph, a brake tripping mechanism comprising an oscillatable arm, means driven from the tone arm of the phonograph for moving said arm in one direction, means driven from the turntable 70 driving mechanism for moving said arm in the opposite direction, and additional lever controlled means controlled by the tone arm for moving the arm in said first direction.

3. In a phonograph, a tone arm, a turntable, a brake therefor and a non-set automatic tripping mechanism for said brake comprising a rack secured to the tone arm, a pinion operated thereby, a shaft secured to said pinion, a ratchet secured to said shaft, a pawl and carrier rotated thereby when said pinion is rotated in one direction, a second pinion freely rotatable on said shaft and rotated in one direction by said carrier, resilient means preventing rotation of said second pinion in the opposite direction, an arm having a hub frictionally engaged between the pawl carrier and said second pinion, said shaft carried mechanism being adapted to move said arm in one 90 direction only, a means for moving said arm in the opposite direction, and a brake tripping mechanism in the path of movement of said arm and adapted to be tripped upon sufficient movement of said arm in said opposite direction.

4. In a phonograph, a tone arm, a turntable, a brake therefor, and a non-set automatic tripping mechanism for said brake comprising a rack secured to the tone arm, 100 a pinion operated thereby, a shaft secured to said pinion, a ratchet secured to said shaft, a pawl and carrier rotated thereby when said pinion is rotated in one direction, a second pinion freely rotatable on said shaft 105 and rotated in one direction by said carrier, resilient means preventing rotation of said second pinion in the opposite direction, an arm having a hub frictionally engaged between the pawl carrier and said second 110 pinion, said shaft carried mechanism being adapted to move said arm in one direction only, a means for moving said arm in the opposite direction, a brake tripping mechanism in the path of movement of said arm 115 and adapted to be tripped upon sufficient movement of said arm in said opposite direction and means for rendering the automatic tripping mechanism ineffective to trip the brake mechanism.

5. In a phonograph, a tone arm, a turntable, a brake therefor and a non-set automatic tripping mechanism for said brake comprising a rack secured to the tone arm, 125 a pinion operated thereby, a shaft secured to said pinion, a ratchet secured to said shaft, a pawl and carrier rotated thereby when said pinion is rotated in one direction, a second pinion freely rotatable on said shaft and rotated in one direction by said 130

carrier, resilient means preventing rotation of said second pinion in the opposite direction, an arm having a hub frictionally engaged between the pawl carrier and said 5 second pinion, said shaft carried mechanism being adapted to move said arm in one direction only, means for moving said arm in said one direction independently of said mechanism, comprising a lever pivoted so 10 that at times one end is depressed by said rack, a resilient device controlled by the other end, said resilient device being in the path of movement of said arm only when the opposite end of the lever is depressed 15 by said rack, a means for moving said arm in the opposite direction, and a brake tripping mechanism in the path of movement of said arm and adapted to be tripped upon sufficient movement of said arm in said 20 opposite direction.

6. In a phonograph, a tone arm, a turntable, a brake therefor and a non-set automatic tripping mechanism for said brake comprising a rack secured to the tone arm, 25 a pinion operated thereby, a shaft secured to said pinion, a ratchet secured to said shaft, a pawl and carrier rotated thereby when said pinion is rotated in one direction, a second pinion freely rotatable on said 30 shaft and rotated in one direction by said carrier, resilient means preventing rotation of said second pinion in the opposite direction, an arm having a hub frictionally engaged between the pawl carrier 35 and said second pinion, said shaft carried mechanism being adapted to move said arm in one direction only, an abutment for said arm, a means for moving said arm in the opposite direction, and a brake tripping 40 mechanism in the path of movement of said arm and adapted to be tripped upon sufficient movement of said arm in said opposite direction.

7. In a phonograph, a turntable, driving and braking mechanism therefor, means operative to prevent operation of said braking mechanism while the tone arm of the phonograph is in initial playing position, and means for rendering the automatic tripping mechanism ineffective to trip the brake 50 mechanism.

8. In a phonograph, a brake tripping mechanism comprising a pronged arm, tone arm controlled means for moving said arm in one direction, turntable driving means for moving said arm in the opposite direction, said latter means comprising a rotatable member, a two part pin resiliently connected together mounted thereon, said pin being 55 adapted to engage the sides of the prongs 60

on said arm, and brake tripping mechanism controlled by said arm.

9. In a phonograph, a tone arm, a turntable driving mechanism and braking mechanism therefor, tripping mechanism for 65 said braking mechanism including a tone arm and an arm moved thereby, means controlled by said latter arm to trip said braking mechanism when moved in one direction and means to permit said tone arm to move 70 said controlled arm in the opposite direction only, whereby movement of the tone arm to initial playing position on the record or swaying movements of the tone arm will not effect a tripping of the braking mechanism. 75

10. In a phonograph, a tone arm, a turntable, driving and braking mechanism for said turntable, and tripping mechanism for 80 said braking mechanism including an oscillatable arm, means connected with said tone arm for moving said oscillatable arm in one direction, means to prevent said tone arm connected means from moving said oscillatable arm in the opposite direction, means 85 connected with the turntable driving mechanism for moving said oscillatable arm in said opposite direction for engaging the tripping mechanism upon sufficient movement of the oscillatable arm. 90

11. In a phonograph, a turntable, driving and braking mechanism therefor, automatic and manual tripping mechanism for said braking mechanism and means whereby the automatic tripping mechanism may be rendered ineffective. 95

12. In a phonograph, a turntable, driving and tripping mechanism therefor, automatic and manual tripping mechanism for 100 said braking mechanism, driving mechanism for said automatic tripping mechanism and means whereby the automatic tripping mechanism may be moved out of engagement with said driving mechanism.

13. In a phonograph, a tone arm, a turntable, driving and braking mechanism for the turntable, manual and automatic tripping mechanism for said braking mechanism, means for effecting a movement of said automatic tripping mechanism comprising 105 a tone arm carried means and means actuated by said turntable driving mechanism, a support for a portion of said automatic tripping mechanism and means whereby said support may be moved so as to disengage the 110 automatic tripping mechanism from its several actuating means. 115

In witness whereof, I affix my signature.

ISAAC BELLOCH.
